United States Patent Office.

E. A. MATTHIESSEN, OF CORNWALL, NEW YORK.

Letters Patent No. 66,368, dated July 2, 1867.

IMPROVEMENT IN GATES.

The Schedule referred to in these Letters Patent and making part of the same.

TO ALL WHOM IT MAY CONCERN:

Be it known that I, E. A. MATTHIESSEN, of Cornwall, in the county of Orange, and State of New York, have invented certain new and useful Improvements in Automatic Gates; and I do hereby declare that the following is a full, clear, and exact description of the same, reference being had to the accompanying drawings, making a portion of this specification, in which—

Figure 1 is a plan or top view of a gate constructed according to my invention.

Figure 2 is a side view of and partial section of the same.

Similar letters of reference indicate corresponding parts in both figures.

This invention relates to that class of gates which are operated to permit the passage of vehicles by the action of such vehicles in approaching or leaving the same; and it consists in a stationary double-inclined plane and two vertically moving inclined planes in combination with a laterally swinging gate, whereby the latter may be made to open in either direction or be brought to a closed position with very great readiness and facility. The invention further consists in a novel means whereby the gate is effectually retained in an open position while a vehicle is passing through the same; and furthermore, in certain novel arrangements of parts, whereby the most efficient operation of the more prominent features of the invention is secured.

To enable others to understand the construction and operation of my invention, I will proceed to describe it with reference to the drawings.

The gate-post *a* is furnished at its inner side, and at a little distance therefrom, with a vertical cylindrical rod, *b*; upon the lower end of which is a supporting washer-plate, *a''*, resting on a suitable fixed plate, *b''*. The gate *A* is attached to this rod *b* by means of two slotted lugs or ears *c*, each of which is furnished with two grooved rollers *a'*, the rod *b* being passed between the said rollers, as indicated more fully in fig. 2, so that the gate may not only swing around upon the rod *b*, but may also move vertically thereon, as hereinafter fully set forth. The other gate-post is shown at *d*, and is furnished with a fixed catch, *b'*, which receives the end of the gate-latch *c'*, to hold the gate in a closed position, (see fig. 1.) Formed adjacent to the post *a*, and extending longitudinally with reference to the roadway, which the gate is designed to close, is a covered cavity or pit, shown at *B* in fig. 2; and extending downward into the upper part of this pit, from the inner end of the gate, is a vertical arm, *e*, the lower end of which is furnished with a friction-roller, *c''*, the said friction-roller resting upon a semicircular bar secured to a suitable support at one side of the pit *B*, and the upper surface of which is formed with two inclines, as shown at *f*, the lower and inner ends of which are joined at *e'*. The length of the friction-roller just mentioned is considerably more than the width of the bar *f*, which, for convenience of description, I denominate the double-inclined plane. So situated as to be capable of moving upward upon the inside of the aforesaid double-inclined plane *f*, is a single-inclined plane, *g*, which, in its cross-section, is of semicircular form, and which is secured transversely upon the upright portion of the inner arm of a lever, *h*, the fulcrum of which is shown at *f'*, and the short or outer arm of which is connected with the inner end of a secondary lever, *i*, pivoted at *g'*, and furnished near its pivoted extremity with a vertical rod, *k*, the upper end of which extends somewhat above the surface of the plank covering *A** of the pit *B*, as shown in fig. 2, and the purpose of which will be hereinafter fully explained. Suspended from the inner end of the lever *h* is a weight, *l*, the bottom of which is flat, and which is situated close to one side of a rectangular frame, *C*, fixed at one side of the pit *B*, underneath the double-inclined plane *f* hereinbefore described. Another inclined plane, marked *m*, also semicircular in its cross-section, and with its upper surface sloping in a direction opposite to that of the inclined plane *g*, is placed outside of the double-inclined plane *f* in such manner that it may move vertically, and is secured upon a lever, *h''*, connected with a lever, *i''*, furnished with an upwardly-extending rod, *k''*, the said levers *h''* *i''* and rod *k''* corresponding to the levers *h* *i* and rod *k*, hereinbefore described, of the inclined plane *g*. The lever *h''* is furnished with a weight, *l''*, similar to the weight *l*, but situated close to that side of the frame *C* opposite such weight *l*. Each of the secondary levers *i* *i''* is furnished with a supplemental weight, *a''*. Pivoted upon the under side of the frame *C* is a plate, *n*, the lateral movement of which is limited by a screw or pin, *n'*, passed through a suitable transverse slot in the said plate. This plate is moved one way or the other by a vertical lever, *r*, pivoted at the top of the frame *C*, and having its cross-bar *r''* connected at each end with a lever, *s*, by means of a link, *s''*, the outermost ends of the levers *s* being provided

with vertical levers t , the upper ends of which extend upward somewhat above the surface of the plank covering A^* , in a manner similar to the corresponding ends of the rods $h h^*$. Secured in any suitable manner upon the covering A^* just mentioned are guides D , which are designed to properly guide or direct the wheels of the vehicle in operating the gate, one pair or set of such guides being placed one upon each side of the upwardly-extending end of each of the rods $h h^*$ and bars t , as represented in fig. 1. Placed over the aforesaid end of each rod $h h^*$ and bar t is an elastic plate, w , attached at one end to the covering A^* , and designed to facilitate the action of the wheels of the vehicle in pressing such rods downward in operating the gate. In order to prevent dirt, dust, &c., from falling through the openings in the covering A^* , through which are passed the upper ends of the rods $k k^*$ and bars t , an apron, x , of cloth, leather, or other like flexible material, is placed over the same, between the aforesaid ends of such rods and bars and the plates w above them. It should be mentioned that the rod k or k^* should be placed at such a distance from the adjacent bar t that the wheels of the vehicle, after having acted upon one, may pass entirely therefrom before acting upon the other.

In operating the gate, one of the forward wheels of the vehicle approaching the same passes between the first or nearest pair of guides D upon the plate w , between the same, and presses downward the bar t underneath. The said bar t , acting through the lever s , link s^* , and lever r , turns the plate n laterally, so that it projects somewhat beyond that side of the frame C toward the vehicle, as is indicated by the position of the said plate as shown in fig. 2; the wheel advancing then passes between the next pair of guides D , upon the plate w thereof, and pressing down rod k or k^* , as the case may be, causes the same to elevate the inclined plane g or m connected therewith, as hereinbefore explained, such inclined plane striking the friction-roller c'' , and raising the gate so that its latch e' is brought clear of the fixed catch b' , whereupon the roller c'' , rolling upon the inclined plane thus elevated, swings or turns the gate around upon the rod b in the direction from which the vehicle approaches, simultaneously with which the weight l or l^* , as the case may be, being raised with the inclined plane connected therewith, catches upon the laterally-projecting edge of the plate n , and, operating somewhat after the manner of a spring-catch, holds the aforesaid inclined plane in its elevated condition, and thus retains the gate in an open position until the wheel of the vehicle, passing between the two pairs of guides D at the opposite side of the gate, forces down the other bar t and moves the plate n laterally to the other side of the frame C , thus releasing the weight l or l^* , as the case may be, and enabling the same, together with one of the weights a^* , to depress the inclined plane to its original position, somewhat below the double-inclined plane f , whereupon the roller c'' , coming upon one of the inclines of the said double-inclined plane, rolls upon the same, and causes the gate to swing inward until the aforesaid roller reaches the most depressed portion a' of the said double incline, whereupon the gate, being brought into a closed position, the latch e' catches upon the catch b' and serves to hold it in its place.

What I claim as my invention, and desire to secure by Letters Patent, is—

1. The fixed double-inclined plane f and the two vertically-moving inclined planes $g m$, in combination with each other and the laterally swinging gate A , substantially as and for the purpose specified.
2. The laterally moving plate n and the weights or catches $b b^*$, in combination with the levers which operate the inclined planes $g m$, whereby the gate is retained in an open position, substantially as herein set forth.
3. The levers $h h^*$, levers $i i^*$, and vertical rods $k k^*$, arranged in relation with each other and with the inclined planes $g m$ and the arm e of the gate A , substantially as and for the purpose specified.
4. The vertical bars t , levers s , and links s^* , arranged with reference to each other and to the lever r and plate n , whereby the said plate may be operated to hold and release the weights or catches $l l^*$, substantially as herein set forth.
5. The guides D , plates w , and aprons x , arranged in relation with each other and with the vertical rods $k k^*$ and bars t , substantially as herein set forth for the purpose specified.

E. A. MATTHIESSEN.
